UNITED STATES PATENT OFFICE.

JEFFERSON C. HOCKER, OF BARNARD, MISSOURI.

SOLE-PROTECTOR FOR BOOTS AND SHOES.

Specification of Letters Patent.

Patented Oct. 3, 1916.

1,200,353.

Application filed October 26, 1915. Serial No. 58,031.

To all whom it may concern:

Be it known that I, JEFFERSON C. HOCKER, a citizen of the United States, and a resident of Barnard, in the county of Nodaway and State of Missouri, have invented an Improvement in Sole-Protectors for Boots and Shoes, of which the following is a specification.

This invention is an improvement in boots and shoes and has particular reference to a protecting device for the soles thereof.

The device contemplated by this invention is preferably adapted for use by miners, lumbermen, stone-workers and, in fact, by all persons engaged in outside employment.

The device may also be constructed to act as an anti-slipping device in inclement weather so that the wearer is effectively prevented from slipping when walking on ice or other smooth and treacherous surfaces.

Another object of the invention is to provide a device attached to the sole of a shoe and secured in position by a novel form of clamp which may be readily and easily operated to detach the device from engagement with the boot or shoe whenever desired.

A further object is the provision of a device of this character which is simple in construction, durable, and effective in carrying out the purpose for which it is designed.

The inventive idea involved is capable of receiving a variety of mechanical expressions, one of which, for the purpose of illustrating the invention, is shown in the accompanying drawing, in which—

Figure 1 is a fragmentary side elevation of the invention, partly broken away and shown in section. Fig. 2 is a fragmentary perspective view thereof. Fig. 3 is a section on the line 8—8 of Fig. 1.

Referring to the drawings, the numeral 11 indicates the usual sole of a shoe to which the protecting device is adapted to be secured.

The sole protector comprises the base plate 24, is preferably made to conform to the general contour of the sole, and has interposed therebetween and said sole a flexible layer 25 preferably made of rubber and having its edges doubled upon themselves to provide a loop 26 through which the wire bail 27 extends. The loop portion 26 is adapted to fit snugly against the upper of the shoe adjacent the point of attachment

thereof with the sole 11 and effectively prevents moisture from gaining access to the latter. The layer 25 is secured in position by means of a plurality of rivets 28 one of which is shown in Fig. 3 of the drawing and provided with a head 29 which will effectively prevent slipping. Adjacent the instep extends a cleat 30 which is adapted to receive the extremities of the wire 27 and which further aids in retaining the side portions of the layer 25 in position.

The clamping means employed comprise a pair of superimposed U-shaped members 31 and 32 adapted to embrace the heel of the shoe, the latter member being provided with offset ears 33 formed at the extremities thereof to which is pivoted the member 31. The rod 34 joins the extremities of the member 32 and is adapted to receive the looped portion of a connection 35 the extremities of which receive therebetween the sole 11. When it is desired to lock the clamp the members 31 and 32 are adjusted to the position shown in Fig. 1 whereupon the latch 36 is swung from the position shown in Fig. 2 to that shown in Fig. 1, the projection 37 carried by said latch extending through the opening 38 formed in the upper member 31 and biting into the heel of the shoe thus preventing accidental displacement of the clamping members. It is to be understood, of course, that these protecting devices together with their clamps may be made in numerous sizes to permit of the use thereof on different sized shoes. To further insure against the accidental displacement of the clamp, the upper member 32 is provided at its intermediate portion and adjacent the latch 36 with a lug 39 which, when the clamp is in position, is adapted to extend between the heel and the upper of the shoe.

I claim:

1. A protecting device for boots and shoes comprising a base plate, a flexible layer interposed between said plate and the sole of a shoe and having its edges projecting beyond the latter and formed into a loop, a wire bail extending through said loop and adapted to retain the layer in engagement with the upper of the shoe whereby to cover the edge of the sole, a clamping device connected to said sole and adapted to embrace the heel of the shoe, said device including a pair of pivoted U-shaped members, and a latch having a projection car-

ried by one of said members, said projection extending through an opening in the other member and engaging the heel of the shoe.

5 2. A protecting device for boots and shoes comprising a sole protecting element, a clamping device connected to said sole protecting element and including relatively adjustable pivoted members for embracing the heel of the shoe, the pivots of said members being horizontal and extending transversely of said sole, and means for securing the members in clamping position.

10 3. A protecting device for boots and shoes comprising a sole protecting element, a clamping device connected to said sole and adapted to embrace the heel of the shoe, said device including a pair of pivoted

U-shaped members, and a latch having a projection carried by said members, said projection extending through an opening in the other member and engaging the heel of the shoe. 20

4. A protecting device for boots and shoes comprising a sole protecting element, a clamping device connected to said sole protecting element and including superposed relatively adjustable pivoted members for embracing the heel of the shoe, and means carried by one of said members and engaging said heel for securing the members in position. 25 30

JEFFERSON C. HOCKER.
